ABSTRACT

An antilock-picking device for lever tumbler locks comprising a plurality of tumblers arranged to engage with a sliding bolt, comprising at least two shaped plates arranged along the same plane as two respective tumblers and mounted for rotation along an axis, each of the plates being provided an extension which is kept in engagement with an edge of the related tumbler coplanar with the other plate by resilient means and with a hook portion which when one of the tumblers is disengaged from the related extension is hooked with the coplanar tumbler due to the action of the said spring means thus preventing the lifting or raising movement thereof.

ANTILOCK-PICKING DEVICE

BACKGROUND OF THE INVENTION

The present invention relates to an antilock-picking device for lever tumbler locks.

The device according to this invention is intended to prevent lever tumbler locks from being picked by means of picklocks.

As known lever tumbler locks which can be controlled by double-profile keys comprise a plurality of tumblers in the form of superimposed plates, in each of which a rectangular shaped opening is formed having a set of teeth along the two longer sides of the opening and arranged opposite to one another. A pin member laterally projecting from the locking bolt is caused to engage between the teeth of the plates. The opposite teeth of each plate may be equal or different in height, while the distance between the outer ends of each pair of teeth opposite to one another is at least equal to the thickness of the pin member. Thus, by moving the plates relative to one another and in a direction normal to the locking direction of the sliding bolt, it is always possible to align a set of superimposed teeth in such a manner so as a passage is defined for the pin member of the locking bolt. This is done by a profile of the key which is also shaped so as to cause, when the same is further rotated, the locking bolt to move for a first stretch, where the said alignment has been established. At the end of each half rotation of the key the pin member is again in an engagement position between the teeth. By further rotating the key the tumblers are caused to move according to the other profile of the key and the alignment of the adjacent different set of superimposed teeth, thus obtaining a further movement of the locking bolt for a second stretch.

As is apparent from the above the locking bolt is moved when the sets of opposite teeth are alternatively aligned in such a manner so as to leave the passage free for the pin member of the locking bolt along the sliding line of the latter.

The locks of the above specified type, however, do not offer a particular resistance to lock-picking in that the key hole, owing to the two opposite profiles formed in the key is rather large, thus allowing a relative easy access inside the lock and an easy use of picklocks.

As known the action of lock-picking consists in forcing back the locking bolt thus making it possible to raise in succession the tumblers with which the pin member of the locking bolt is engaged.

SUMMARY OF THE INVENTION

One object of the present invention is to provide a device in which such lock-picking possibility is substantially eliminated.

The antilock picking device according to the invention is characterized in that it comprises at least two shaped plates arranged in the same plane as any pair of tumblers and mounted for rotation around an axis, each of the said plates being provided with an extension which is kept in engagement relationship with the edge of related tumbler coplanar with the other plate by resilient means, and with a hook portion which when one of the tumblers is disengaged from the related extension is hooked with the coplanar tumbler due to the action of the spring said means, thus preventing the lifting movement thereof.

BRIEF DESCRIPTION OF THE DRAWING

The invention will better appear from the following description with reference to the accompanying drawing, in which:

FIG. 1 is a general view of the inside of a lever tumbler lock provided with the device according to this invention; and

FIG. 2 shows a device according to the invention in an operative condition;

FIG. 3 is a perspective view of the device shown in FIG. 2.

DESCRIPTION OF THE PREFERRED EMBODIMENT

With reference to the above figures, a lever tumbler lock according to the invention comprises a housing or casing generally indicated at 1 which is mounted on a face plate element 2 by fixing means 3. From the side or back 44 of the housing four threaded bushings 5 project upwards in which screws holding a cover (not shown) tightening the same on the edge 6, are threaded.

The plate 2 has a frontal opening through which a locking or sliding bolt 7 can slide. The bolt 7 has a rear extension 8 formed with teeth 9 in the lower portion thereof and with a straight eyelet opening 10 in which a guide pin 11 rigid with the bottom 4 of the housing 1 can slide. In this manner the sliding bolt 7 is guided in a horizontal direction, viewing FIG. 1.

A pin member 12 is laterally rigid with the extension 8. The pin member 12 extends normally to the sliding bolt 7 and is of a square cross-section and allows engagement between the sliding bolt 7 and the tumblers 13. The latter can be any in number. In a preferred embodiment the pin member 12 projects from both sides of the extension 8 and the tumblers 13 are arranged partly on the face in view of the extension 8 and partly on the opposite face. For clarity sake, however, only one of them is illustrated in FIG. 1, the others being wholly similar to it. Each tumbler 13 is formed from a shaped plate provided with two eyelets or windows 14 and 15 in engagement relationship with the threaded bushings 5, the latter guiding the said plates in a direction at right angles relative to the moving direction of the sliding bolt 7.

Each plate has also a cut out portion 16 into which a double-profile key can be inserted through the key hole 17 in the housing 1.

A rectangular opening 18 is formed in each tumbler, along the longer sides of which two sets 19 and 20 of teeth spaced from one another are provided which are arranged to receive the pin 12.

It should be noted that the distance between the opposite free ends of the teeth of the relative tooth sets 19 and 20 is just enough to allow the passage of the pin member 12, and the teeth alternatively have the same height. Of course the heights of the teeth in the various tumblers can be different from one another so as to define two alternate sets of superimposed teeth arranged to define a passage for the pin member 12 only when the teeth of each set are moved relative to one another and to the pin member 12 according to a relation corresponding to the code of the tumbler lock.

The movement of each tumbler occurs against the action of a rat-tail or tang spring 21 which has one end thereof rigid with the tumbler and the other end thereof

abutting on the edge 6. The antilock-picking device according to the present invention consists of a pair of shaped plates 22a and 22b pivoted on the pivot pin 23 rigid with the bottom 4 of the housing 1. The plates 22a, 22b are housed in a recess of the housing 1 and lie on the planes of two corresponding tumblers 13. The tumblers coplanar with the plates 22a and 22b are indicated at 13a and 13b, respectively, in FIG. 2.

The plates 22a and 22b are substantially equal in shape. They have extensions 24 and 25 shaped in such a manner so as due to the urging action of the rat-tail or tang springs 26 the free ends thereof engage suitably inclined portions of the rear edges of the tumblers 13b and 13a, respectively. The plates 22a and 22b are also formed with two hooked portions 27 and 28 arranged to engage, as will better appear hereinafter, with relative stepped portions 29 and 30 formed in the coplanar tumblers 13a and 13b.

The operation of the antilock-picking device according to the invention is as follows. As described above 20 the lock-picking action consists in raising the tumblers so as to cause the sets of teeth 19 and 20 to define passages at the level of the pin member 12 thus allowing the sliding movement thereof.

With the device according to the present invention 25 this sliding movement is prevented in that when one of the tumblers 13a and 13b is caused to raise, the other pin is hooked and thus cannot be raised. In fact, by causing the tumbler 13b to raise, the extension 24 of the plate 22a is no more engaged and due to the action 30 of the spring 26 the plate 22a is caused to rotate and

the hook portion 27 engages with the step portion 29 of the tumbler 13a thus preventing the raising movement thereof.

It should be noted that the lifting movement of the 5 two tumblers 13a and 13b at the same time is ineffective in that in order to free the passage for the pin member 12 it is necessary to lift one of them to a greater or lesser extent relative to the other according to the code of the lock, this being instead possible by making use 10 of a proper key.

I claim:

1. An antilock-picking device for lever tumbler locks comprising a plurality of tumblers arranged to engage with a sliding bolt, characterized in that it comprises at least two shaped plates arranged in the same plane as any pair of said tumblers and mounted for rotation around an axis, each of said plates being provided with an extension which is kept in engagement relationship with an edge of the related tumbler coplanar with the other plate by resilient means and with a hook portion which when one of the tumblers is disengaged from the related extension is hooked with the coplanar tumbler due to the action of the said spring means thus preventing the lifting movement thereof.

2. A device as claimed in claim 1, wherein the said spring means consists of rat-tail or tang springs secured at one end thereof to the related plate and abutting on the inner surface of the housing of the lock with the other end thereof.
